UNITED STATES PATENT OFFICE.

CLINTON D. TABOR, OF NEW YORK, N. Y., ASSIGNOR OF ONE-HALF TO
ALBERT SCHRAFFT, OF NEWARK, NEW JERSEY.

WINDOW-SASH.

SPECIFICATION forming part of Letters Patent No. 621,953, dated March 28, 1899.

Application filed November 22, 1898. Serial No. 697,131. (No model.)

To all whom it may concern:

Be it known that I, CLINTON D. TABOR, a citizen of the United States, residing at New York, in the county of New York and State of 5 New York, have invented new and useful Improvements in Window-Sashes, of which the following is a specification.

This invention relates to that class of window-sashes which can be raised and lowered 10 in the usual manner for opening and closing the window and which can also be reversed, so that either side of the sash is accessible from the inside of the building for cleaning or repairing the same, so as to avoid the danger attending cleaning and repairing windows 15 from the outside of the building.

The object of my invention is to produce a window-sash of this character which is simple and durable in construction and reliable in 20 operation and which can be conveniently detached from and attached to its supports.

In the accompanying drawings, consisting of two sheets, Figure 1 is an inside elevation, partly in section, of a window provided with 25 my improved sashes, showing the upper sash slightly tilted. Fig. 2 is a vertical transverse section of the same in line 2 2, Fig. 1. Fig. 3 is a fragmentary vertical section, on an enlarged scale, of the lower sash in line 3 3, Fig. 30 2, showing the same in its normal operative position. Fig. 4 is a perspective view of one of the guide-bar sockets which receives one 35 of the pivots of the sash. Fig. 5 is a fragmentary edge view of one of the guide-bars and the socket attached thereto and showing the pivot seated therein in section. Fig. 6 is a fragmentary edge view of one of the stiles of the window-sash and its pivot. Fig. 7 is a fragmentary horizontal section in line 7 7, 40 Fig. 3, showing the sash in its normal operative position. Fig. 8 is a similar view showing the position of the parts when the sash is turned slightly on its pivot. Figs. 9 and 10 are fragmentary horizontal sections in lines 45 9 9 and 10 10, Fig. 3, respectively. Fig. 11 is a fragmentary vertical section in line 11 11, Fig. 3. Fig. 12 is a fragmentary vertical section similar to Fig. 3, showing one of the guide-bars held in a retracted position against the 50 side jamb of the frame. Fig. 13 is a horizontal section in line 13 13, Fig. 12. Fig. 14 is

an end view of one of the side-jamb thimbles which receives one of the guide-bar catches.

Like letters of reference refer to like parts in the several figures.

55

The window-frame may be of any usual and well-known construction and consists, essentially, of two vertical pulley or side jambs A A, a head-jamb B, connecting the upper ends of the side jambs, and a sill C, connecting the 60 lower ends of the side jambs. The inner side of each side jamb is provided with the usual inner stop D, intermediate stop D', and outer stop D², which extend vertically from the sill to the head-jamb and form an inner guideway 65 d and an outer guideway d' between these stops.

E E' represent the upper and lower sashes, which abut with their check-rails e e' and engage with their top and bottom rails e² e³ 70 against the head-jamb and sill, respectively, when the sashes are in their normal position, the same as in the sashes now commonly used. The width of each sash, or, in other words, the distance between the outer edges e⁴ of the 75 stiles e⁵ of each sash, is less than the distance between the stops D D' D² on one side jamb of the frame and the corresponding stops on the side jamb on the opposite side of the frame, which permits the sash to pass freely 80 between the two sets of stops.

F represents vertical guide-bars whereby the sashes are guided in their vertical movements and upon which the sashes may be swung in a vertical plane for turning either 85 side of the sashes inwardly. One of these bars is arranged in each of the guideways and bears with its inner longitudinal edge against the opposing edge of the adjacent sash-stile, the pair of guide-bars on the opposite sides of the lower 90 sash being arranged in the inner guideways d and the pair of guide-bars on opposite sides of the upper sash being arranged in the outer guideways d'. The guide-bars on opposite sides of each sash are of the same length and 95 flush with the top and bottom thereof and are connected with counterbalancing-weights g by cords g', passing around pulleys g² on the side jambs. One side of each stile, preferably the outer side f, is of such width that it 100 practically fills the space between the adjacent outer edge of the sash-stile and the back

of the adjacent guideway, while the opposite or inner side f' thereof is of a width less than said space, which permits the narrow portion of the guide-bar to rock to a limited extent 5 in a horizontal plane toward and from the outer edge of the adjacent sash-stile. The guide-bar during this rocking movement turns with its corner f^2 at the juncture of the outer side and outer edge thereof in the adjacent corner of the guideway as a pivot. 10 Each of the guide-bars is provided on its inner edge near its inner side with a longitudinal rib or tongue h , which engages with a corresponding groove h' in the opposing outer edge of the adjacent sash-stile.

Each of the sashes is connected with the central portions of its stiles to the central portions of its guide-bars by horizontal coupling-bolts I , so that the sash and its bars move 15 up and down together and the sash can turn in a vertical plane on the guide-bars. Each of these bolts is guided in a frame fitted in a recess in the outer edge of a sash-stile and consists of a face-plate j , through which the middle portion of the bolt passes, and a yoke j' , through which the inner portion of the bolt passes. The outer edge of the coupling-bolt is provided with a head j^2 , having a conical or convex back side. 20

The coupling-bolt is constantly drawn inwardly by a spring k , surrounding the bolt and bearing with its ends against the inner side of the face-plate, and a washer k' , which in turn bears against a pin k^2 on the bolt. 25

L represent sockets which receive the headed ends of the coupling-bolts and which are arranged on the inner edges of the guide-bars. Each of these sockets consists of a face-plate l , secured over a recess l' in the inner edge of the guide-bar and provided 30 with a slot consisting of a vertical portion l^2 and a horizontal portion l^3 , which extends laterally from the upper end of the vertical portion and opens inwardly through the guideway. For the purpose of connecting the sash with its guide-bars the heads of the coupling-bolts are first slipped into horizontal portion l^3 of the socket-slots, this operation being facilitated by limiting the inward movement of each bolt, so that in its innermost position its head projects beyond the outer edge of the sash-stile. The inward movement of the coupling-bolt is preferably limited by engaging the washer k' or the pin k^2 with the yoke j' . After the coupling-bolts have been slipped into the horizontal portion of the socket-slots the bolts are pressed downward into the vertical portion of the slots until the bolts engage with the lower ends thereof. As the bolts move downwardly in the sockets the head of each bolt engages with its back side against inclines m , arranged on the face-plate on opposite sides of the vertical portion of the slot, whereby the bolt is moved toward the guide-bar and the spring k is strained, thereby causing the guide-bar and sash to be firmly drawn together, so as to prevent leak-

age and rattling at the joints. In the lowermost position of the coupling-bolts the heads thereof engage with vertical bearing-faces m' on opposite sides of the socket-slot, which causes the spring to draw the head of the bolt squarely against the socket and prevents the tension of the spring from displacing the bolt in the socket, which would be liable to happen if the head of the bolt rested against an incline when in its operative position. 70

When the sash is connected with the guide-bars by the coupling-bolts and the sash is in its normal vertical position, the springs k serve to retain the sash in this position by yieldingly holding the ribs h of the guide-bars in engagement with the grooves of the sash-stiles, thereby causing the sash to rise and fall with the guide-bars when opening and closing the window. When it is desired to reverse the sash for cleaning the pane or for other purposes, it is turned on the coupling-bolts as a pivot, whereby the upper and lower ends are swung in opposite directions. This movement of the sash causes the curved or inclined sides of its grooves to engage with the corresponding sides of the ribs on the guide-bars on the principle of a wedge and turn or deflect the same in a horizontal plane, 85 as shown in Fig. 8, so that the ribs clear the grooves and permit the sash to be swung freely into any desired position. Upon returning the sash to its normal vertical position the guide-bars are instantly drawn horizontally against the stiles and their ribs are again engaged with the grooves in the stiles. The wedge action of the sash against the guide-bars is preferably produced by making the ribs of rounded or convex form and the groove in the stile of corresponding form; but, if desired, the rib on the guide-bar and its co-operating groove in the sash-stile may be of tapering or conical form. The corner f^2 , on which the guide-bar turns, preferably has the form of a narrow rib or flange, as shown in the drawings, which permits that side of the guide-bar to fit snugly between the sash-stile and the back of the guideway, thereby preventing leakage between the guide-bar, sash, and frame, and it also forms a small contact-surface between the guide-bar and the guideway, thereby reducing the friction and wear upon the parts and also permitting the sash to be opened and closed easily, because the tendency to bind is reduced to a minimum. 100

When it is desired to remove the sash from the guide-bars for repairs or other purposes, this can be accomplished by raising the sash so that its coupling-bolts are lifted from the bottom to the top of the vertical portions of the socket-slots and then drawing the sash horizontally inward, whereby the coupling-bolts are moved through the horizontal portions of the socket-slots, thereby detaching the sash from the guide-bars. Preparatory to removing the lower sash the latter is raised, together with its guide-bars, sufficient to clear the lower stop n on the sill, and for the same 105 110 115 120 125 130

purpose the upper sash is lowered with its guide-bars, so as to clear the upper stops n' on the head-jamb.

For the purpose of permitting the sashes 5 to be easily and conveniently detached from and attached to the guide-bars each of the latter is held stationary during the operation of detaching and attaching the sashes by a retaining device, which is constructed as follows:

O represents a depending catch, which is arranged in an outwardly-opening recess o' in the lower end of a guide-bar. This catch is provided at its lower end with an inclined 15 hook o^2 , which extends upwardly and laterally toward the adjacent guide-bar, and its upper end is provided with a vertical slot o^3 , which receives a transverse pin o^4 on the sash-stile.

P represents a cylindrical thimble arranged 20 in the back of each guideway near the lower end thereof and provided on its upper side with a transverse shoulder or lip p , having an inclined inner side p' , which extends from 25 its lower end upwardly and laterally away from the adjacent guide-bar. In the lowermost or closed position of the lower sash its catches engage with the sill and are raised in the sash-stiles, as shown in Fig. 3, this 30 movement of each catch being permitted by the slotted connection of the catch with the stile. The catches of the upper sash when in its lowermost position are raised in the stiles thereof by engagement with the sill in 35 the same manner as the catches of the lower sash. In the elevated position of the sashes the catches thereof drop until the upper ends of the slots therein engage with the supporting-pins o^4 , in which position of the catches 40 their hooked lower ends project below the stiles. When it is desired to detach the lower sash from its guide-bars, the latter, together with the lower sash, are raised until they clear the bottom stop n , and the catches thereof 45 depend below the stiles and stand opposite the catch-thimbles in the guideways d . The catches are now swung laterally out of the recesses o' , so that they stand at an angle to the guide-bars and their hooks are engaged 50 with the inclined lips of the thimbles, as represented in Fig. 12, whereby the guide-bars are held against further upward movement. Upon now moving the sash upwardly and inwardly its coupling-bolts are disengaged from 55 the bolt-sockets.

When the sash is disengaged from the guide-bars, the upward pull upon the latter by the counterbalancing-weights causes the inner or narrow portion of the guide-bars to 60 be drawn horizontally backward toward the guideways by the catches, as represented in Figs. 12 and 13, whereby the guide-bars are held in a retracted position, so that their ribs clear the path of the sash and permit the latter to be conveniently inserted between the guide-bars. The backward or outward movement of each guide-bar is produced by the

tendency of its catch to straighten itself out vertically with reference to its guide-bar and the line of draft on the principle of a toggle-joint, and this movement of the guide-bar is aided by the wedge action of the inclined hook of the catch against the inclined shoulder of the thimble. The thimbles of each pair of guide-bars are arranged horizontally 70 in line, so that the guide-bars are retained at the same height by the catches, thereby permitting the coupling-bolts of the sash to be easily reengaged with the sockets. Upon lowering the sash and its guide-bars after the 80 sash and bars are coupled the catches disengage themselves automatically from the thimbles by gravity, aided, if necessary, by the inclined hooks of the catches engaging with the lower edges of the thimbles, whereby the 85 catches are forced inwardly into the recesses of the sash. The catches are retained in these recesses with their hooks clear of the thimbles by gravity, so that in the normal position of these parts the sash can be freely raised and 90 lowered.

The upper sash is preferably lowered in its guideways when it is desired to remove the same from its guide-bars so as to be within convenient reach, and for this purpose the 95 thimbles for the reception of its guide-bar catches are arranged near the lower ends of the outer guideways d' , as shown in Fig. 2.

The detachable connection between the sash and its guide-bars is particularly desirable 100 when the full opening of the window is required—for instance, when moving large furniture through the window.

The removability of the sashes from the guide-bars is also very desirable when the 105 window is provided on its outer side with a screen which extends the full height of the window. When such screen is used, the sashes cannot be reversed for cleaning, because the screen is too close to the sash, and 110 the latter therefore has to be removed from the guide-bars in order to afford proper access to both sides of its pane. The removal of the sashes is permitted without removing the guide-bars from the frame and disconnecting the same from the sash cords and 115 weights.

I claim as my invention—

1. The combination with a window-frame provided with a guideway and a sash which 120 clears said way, of a guide-bar capable of turning transversely in said guideway and bearing against said sash, and a pivot connecting the sash with the guide-bar, substantially as set forth.

2. The combination with a window-frame provided with a vertical guideway and a sash which clears said way, of a horizontally-swinging guide-bar arranged between said guideway and the edge of the sash and bearing pivotally with one of its edges against said guideway and provided on its opposite edge with an incline which engages with an incline on the sash, and a bolt pivotally connecting the

sash and the guide-bar, substantially as set forth.

3. The combination with a window-frame provided on opposite sides with vertical guide-ways and a sash which clears said ways, of horizontally - swinging guide-bars bearing with their inner edges against opposite vertical edges of the sash and arranged with their outer edges in said ways, one side of each bar being as wide as the space between the sash and the back of the adjacent way and provided with a fulcrum at the corner of the outer side and the outer edge of the bar and the opposite side of the bar being narrower than said space and capable of moving toward and from said sash, a tongue or rib arranged on the inner edge of each bar adjacent to the opposite side thereof and engaging with a groove in the adjacent edge of the sash, and horizontal bolts pivotally connecting the sash with said bars, substantially as set forth.

4. The combination with a window-frame provided on opposite sides with vertical guide-ways and a sash which clears said ways, of horizontally - swinging guide-bars arranged between said ways and opposite edges of the sash, pivot-bolts connecting said bars with the sash, and springs mounted on the sash and adapted to draw the bars against the sash, substantially as set forth.

5. The combination with a window-frame provided on opposite sides with vertical guide-ways, guide-bars arranged in said ways and provided with laterally-opening sockets, and a sash arranged between the guide-bars, of pivots mounted on the sash and provided at their outer ends with shoulders or heads which engage with shoulders on the sockets of the guide-bars, and springs mounted on the sash and tending to draw the pivots inwardly so as to draw the bars against opposite sides of the sash, substantially as set forth.

6. The combination with a window-frame provided on opposite sides with vertical guide-ways, of guide-bars arranged in said ways and each provided with a slotted socket having a vertical slot and a horizontal slot which extends laterally from the upper end of the vertical slot, and pivots arranged on the sash and engaging with the slots of said sockets, substantially as set forth.

7. The combination with a window-frame provided on opposite sides with vertical guide-ways, of guide-bars arranged in said ways,

slotted sockets arranged on said bars and each provided with a vertical slot, a horizontal slot extending laterally from the upper end of the vertical slot, and an incline adjacent to the inner side of the vertical slot, a sash arranged between said guide-bars, coupling-bolts arranged in guide-frames on the sash and in the slots of the sockets, heads arranged on said bolts and adapted to engage with the inclines of the sockets, and springs arranged on the sash and adapted to shift the bolts and draw their heads against the inner sides of said sockets, substantially as set forth.

8. The combination with the window-frame provided on opposite sides with vertical guide-ways and with shoulders or thimbles in the lower portions of said ways, of guide-bars sliding vertically in said ways and each capable of turning horizontally on one of its edges as a fulcrum, a catch arranged near the opposite edge of the bar and adapted to engage with the shoulder or thimble in the adjacent guideway for holding the bar in a lowered and in a turned position, and a window-sash having pivots which are detachably journaled on said bars, substantially as set forth.

9. The combination with a window-frame provided on opposite sides with vertical guide-ways, of horizontally - swinging guide-bars arranged in said ways, balancing devices connected with said bars, catches arranged on said bars and provided with inclined hooks which engage with inclines on said frame, and a sash detachably connected with said bars, substantially as set forth.

10. The combination with a window-frame provided on opposite sides with vertical guide-ways, of thimbles arranged in the backs of said ways and provided with inclined shoulders, horizontally - swinging guide-bars arranged in said ways, balancing-weights connected with said bars, catches provided with slots which receive pins on said bars and with hooks which are adapted to engage with said shoulders, and a sash detachably connected with said bars, substantially as set forth.

Witness my hand this 15th day of November, 1898.
